CATAFALQUE

James A. Badger, Malone, N. Y.

Application June 5, 1939, Serial No. 277,530

2 Claims. (Cl. 248—166)

This invention relates to catafalque construction, the primary object of the invention being to provide a catafalque of a folding and adjustable character, to the end that the catafalque may be readily and easily transported and readily set up for use.

Another object of the invention is to provide a device of this character comprising a box-like body portion having a hinged cover, the body portion acting as a container for the drapes and various articles used in connection with the catafalque, when set up.

10. Another important object of the invention is to provide a catafalque of the character which

15. may be extended to meet various requirements of use, to the end that the device may be effectively used as a cooling board or slumber couch.

With the foregoing and other objects in view, which will appear as the description proceeds, the 20 invention resides in the combination and arrangement of parts and in the details of construction hereinafter described and claimed, it being understood that changes in the precise embodiment of the invention herein described, may be 25 made within the scope of what is claimed, without departing from the spirit of the invention.

Referring to the drawing:

Figure 1 is a longitudinal sectional view through 30 a catafalque constructed in accordance with the invention, showing the same in an extended position.

Figure 2 is a plan view thereof, the drapes, used in connection with the device, being removed.

35. Figure 3 is a sectional view taken on line 3—3 of Figure 2.

Figure 4 is a sectional view taken on line 4—4 of Figure 2.

Figure 5 is a sectional view taken on line 5—5 of Figure 2.

40. Figure 6 is a sectional view taken on line 6—6 of Figure 2.

Figure 7 is a plan view of the folding cooling board which may be positioned on the device for 45 use as a slumber couch.

Figure 8 is a sectional view through the telescoping members of the adjustable frames.

Referring to the drawing in detail, the catafalque embodies a box-like body portion comprising 50 the rectangular frame 5, the sides and bottom thereof being covered by means of the siding 6, which may be constructed of any suitable light material, to facilitate the transporting of the device.

55. The reference character 7 designates the cover

of the body portion, which is hingedly connected to one of the sides 6, at 8, there being provided pivoted fasteners 9 at the opposite end of the cover for securing the cover in its closed position.

The handle 10, by means of which the catafalque is carried, is removably secured to the cover 7, the ends of the handle being extended through the eye members 11, carried by the cover.

The reference character 12 designates the adjustable frames, which are substantially U-shaped 10 in formation, and have their ends slidably mounted under the straps 13, which are secured to the cover 7.

The strips 6 which cover the ends of the body portion, are formed with recesses for the reception 15 of the bars 14, which are slidably mounted therein, the bars being provided with spaced openings for the reception of the pins 15 which also pass into openings of the upper bars of the ends of the rectangular frame 5. Thus it will be seen that due to this construction, the bars may be extended laterally to various positions. The outer ends of the bars 14 are provided with hooks 16 that are held in position by means of the slots 17, the hooks being designed to engage the outer 20 ends of the U-shaped frames 12, securing the bars to the frames.

Leg members 18 are connected to the bars 14, at the outer ends of the bars, the leg members 30 being mounted so they will fold upwardly into close engagement with the bars, so that they may be readily transported. Pivoted brace arms 19 connect the leg members and bars 14, so that when the leg members are moved to their extended positions as shown by Figure 1, they will be securely held against folding inwardly.

Rubber supporting buttons indicated at 20 are positioned on the cover 7, and provide means for supporting the casket, which is positioned 40 thereon.

In Figure 7 of the drawing I have illustrated a removable top for the device, which is in the form of a board having pivoted end sections 21, which may be moved to the positions as shown by Figure 7, so that the device may be used as a cooling board or slumber couch. Because of the pivoted end sections, it is obvious that the length of the removable top may be adjusted to meet various requirements.

50. The drapes which are used in connection with the device, are indicated by the reference character 22, and are provided with hooks at their upper ends, to be hooked over the adjustable frames 12, to support the drapes. It will of course 55

be understood that these drapes are of lengths to reach to the floor or supporting surface on which the catafalque is positioned.

From the foregoing it will be seen that due to 5 the construction shown and described, I have provided a catafalque of the adjustable type, and one which may be readily and easily transported. It will also be seen that the body portion of the catafalque is such that it provides a case in which 10 the various articles used in connection with the catafalque may be carried.

It might be further stated that the arms of the adjustable frames 12 are adapted to telescope as shown by Figure 8 of the drawing, when the 15 frames 12 are moved to their inactive positions.

What is claimed is:

1. A catafalque comprising a body portion in the form of a box, a cover hingedly connected to the body portion, straps secured to the upper side 20 edges of the body portion, U-shaped frames embodying side bars, slidably mounted within the straps, bars having lines of spaced openings, dis-

posed between the side bars and extended in parallel relation with the side bars, pins on the body portion and adapted to extend into the opening holding the U-shaped frames in various positions of adjustment, leg members pivotally connected to the outer end of the U-shaped frames, a flexible cover, hooks secured to said cover and adapted to hook over the frames and body portion, closing the space around the catafalque. 5

2. A catafalque comprising a box-like body 10 portion, a cover hingedly connected to the body portion, U-shaped side frames slidably connected with the body portion and adapted to extend beyond the ends of the body portion, means for securing the U-shaped frames in various positions 15 of adjustment, a flexible cover, hooks secured to said cover and adapted to fit over the U-shaped frames, closing the space around the catafalque, and a removable table having pivoted end portions, adapted to be extended over the upper surface of the body portion and U-shaped frames. 20

JAMES A. BADGER.
